LESTER J. WOLF, OF SOUTH BEND, INDIANA, ASSIGNOR TO WESTINGHOUSE ELECTRIC
& MANUFACTURING COMPANY, A CORPORATION OF PENNSYLVANIA

SYNCHRONIZING SYSTEM

Application filed December 9, 1927. Serial No. 238,823.

My invention relates to radio broadcasting and particularly to the problem of maintaining two separated broadcasting stations at the same wave length.

5 An operator using a receiving set placed at a distance from each of two broadcasting stations sending the same program may choose from which station he will get the program by tuning to the wave length of one or 10 the other station. The effects of fading often interfere more effectually with the reception from one broadcasting station than from another. If the two broadcasting stations work on the same wave length the signal will be received from that station which 15 is least affected by the fading and the listener will hear it without knowing or caring from which broadcasting station it arrived.

If the advantage of two separated broadcasting stations working on the same wave length is to be obtained, the wave lengths must be exactly equal, otherwise there will be a beat-note in the receiving set which ordinarily will completely spoil the reception of 25 the signals. Any means for maintaining the wave lengths at two broadcasting stations alike will fail to accomplish useful results unless the equality of the wave length is maintained with great accuracy. A very small percentage change in the wave length 30 at one station will be sufficient to produce a perceptible beat-note in any receiving set which is within reach of both stations.

Attempts made heretofore to maintain two stations in synchronism by sending a synchronizing impulse from one station to the other at periodic intervals have failed because the action of fading, of static or of both has interfered with the reliable transmission of the synchronizing impulses.

It is an object of my invention to produce a reliable system for maintaining the wave length of separated broadcasting stations at the same value.

45 It is a further object of my invention to

produce a low frequency at each station to maintain said low frequencies equal by control impulses transmitted from one station to the other and to produce, at each station, from the low frequency there a frequency 50 capable of radiation. In this way, I can maintain the two radiation frequencies equal.

If an oscillating system be provided with regenerative arrangements, that is, with means whereby the energy delivered by the system at one point is made to control the supply of energy to the system at another point, the manner in which the system will oscillate is dependent on the degree of regeneration, if the regeneration is not large 55 enough to overcome the damping, the oscillations will die away. If it is almost but not quite enough to completely counteract the damping, the rate of decay of the oscillations will be small and the system will 60 continue in oscillation for some time after the stimulus which caused the oscillations has ceased. Theoretically, it is possible to provide a degree of regeneration which would just compensate for the damping and the 65 system then would, if set into oscillation, continue to oscillate at a constant amplitude. If the regeneration be greater than this, the 70 oscillations will increase in amplitude, and, if the regeneration be sufficiently great, the 75 oscillations will start from such insignificant stimuli that they are called spontaneous.

I have discovered that it is possible to control the frequency of the oscillations provided the desired frequency does not differ much from the natural frequency of the regenerative system and provided further that the degree of regeneration is properly chosen. The proper degree of regeneration 80 for this purpose is large enough to prevent the decay of the oscillations from being rapid and small enough to avoid spontaneous oscillations.

85 It is an object of my invention to apply 90

this discovery to the control of the frequency of a remote broadcasting station.

It is a further object of my invention to provide at one broadcasting station a mechanically oscillating system maintained in oscillation by regenerative arrangements, and to provide at a remote broadcasting station an oscillating system supplied with a regenerating arrangement adjusted, as explained above, to such a degree of regeneration that the frequency may be controlled by impulses from the first mentioned broadcasting station.

It is a further object of my invention to convey the frequency-controlling impulses from the mechanically oscillating system in one station to that in the other by means of a modulation impressed upon a carrier frequency.

It is a further object of my invention to provide the said carrier frequency by developing it from the said mechanically oscillating system.

It is a further object of this invention to develop from the same mechanically oscillating system, a suitable frequency for the broadcasting carrier wave.

Other objects of this invention and details of the construction will be apparent from the following description and the accompanying drawings, in which:

Figure 1 is a diagram of the circuits and apparatus involved;

Fig. 2 is a diagram of the circuits associated with the mechanically oscillating system at the controlled station;

Fig. 3 is a diagram of the circuits and apparatus employed for multiplying the frequency.

At the sending station, a tuning fork 1 is employed as a source of mechanical frequency. Other sources of mechanical frequency, having a natural period such as pendulums, watch balance wheels, constant-pressure turbines, centrifugal governors and the like, may be used instead of a tuning fork if desired. Piezo-electric crystals also are suitable for this purpose.

Upon one tine of the fork 1, the coil 2 is provided which is connected to the input of an amplifier 3. The output of the amplifier is connected to the winding of a magnet 4 associated with the other tine of the fork. Preferably, a member 5 of magnetic material is located between the free ends of the tines.

The output of the amplifier 3 is also connected to a modulator 6 by means of which the oscillations developed in an oscillation generator 7 are modulated in accordance with the movement of the fork. The oscillations are delivered to an antenna 8 by which they are broadcast.

The output of the amplifier 3 is also delivered to a frequency multiplier 10 which is

caused to control the frequency of an oscillator 11. The oscillator may be merely a power amplifier connected with the last tube of the frequency multiplier. The output of the oscillator is delivered to an antenna 12 from which the signal is broadcast.

The radiation delivered by the antenna 8 is received upon an antenna 15 near the remote broadcasting station. Any suitable receiving set 16 produces from these oscillations a current corresponding to the modulation thereof, that is a current corresponding to the movement of the fork 1. The current is amplified by the amplifier 17 and impressed upon a line 18 by which it is conveyed over a short distance to the remote broadcasting station. It is then impressed upon a filter 19 through which it is delivered to an amplifier 20 and, after passing through a filter 21, is impressed upon a driving magnet 22 of a fork 23. The fork 23 is as nearly equal in frequency to the fork 1 as can be conveniently provided.

The fork 23 is equipped with the driving magnet 22, the output coil 24 and the magnetic member 25, similar in function to the corresponding parts at the first broadcasting station.

The output coil 24 delivers an electromotive force to the grid and filament of a vacuum tube 26. The output of this vacuum tube is impressed upon the same amplifier 20 to which the output of the filter 19 is connected. The output coil 24 is also connected to a frequency multiplier 30 which controls the oscillator 31 in the same way that the frequency multiplier 10 controls the oscillator 11, the oscillator 31 delivers energy to the antenna 32 from which the broadcasting action is radiated.

The signal originates at the microphone 35 which is located in a studio or at the scene of the program to be broadcast. This may be remote from one or both of the broadcasting stations.

The signal is amplified by amplifier 36 and is impressed upon the line 37. A filter 38 at one end of this line connects the line to the modulator 39, by which the output of the oscillator 11 is modulated. The line 37 is also connected through a filter 41 to the modulator 42 which modulates the output of the oscillator 31. The signals impressed upon the microphone 35 are thus reproduced as modulations upon the energy broadcast from the antennæ 12 and 32.

The receiving set 16 upon which the energy radiated from the antenna 8 is received is of any desired or suitable type. For example, it is convenient to have in the apparatus 16 both a receiver of the neutrodyne type and a receiver of the superheterodyne type with arrangements for switching from one to the other, whereby that one may be selected which is best adapted to the con-

ditions prevailing at the time. When two different receiving sets are used it is practical to use the same amplifier 17 for either set.

The connection between the line 18 and the filter 19 is preferably made by means of a transformer 45. The impedance of the line is thus conveniently correlated with the impedance of the filter 19 and amplifier 20. A connection 47, Fig. 2, to the midpoint of the primary of the transformer 45 is controlled by a signal device such as the key 48 by means of which the switching arrangements at the receiver 16 may be manipulated. If desired, the arrangements in the station at antenna 15 may include signalling devices. The key 48 then affords means for communication between the remote broadcasting station at antenna 32 and the receiving substation at antenna 15.

The output of the filter 19 is connected to the amplifier 20 which, as illustrated in Fig. 2, comprises two portions, one portion being between the filter 19 and the tube 26 and the other portion being between the tube 26 and the driving magnet associated with the fork.

As illustrated in Fig. 2, the first portion of the amplifier 20 includes two tubes 50 and 51 arranged in cascade. The output of the tube 51 is connected to the input of the tube 52 which is the first tube of the second portion of the amplifier. This portion also comprises a plurality 52, 53 of tubes arranged in cascade. The connection between the two portions comprises a link circuit 54 uniting the output transformer 55 of the tube 51 with the input transformer 56 of the tube 52.

The connection from the output coil 24 of the fork 23 to the amplifier is made by the way of this link circuit. The connection includes a potentiometer 57 comprising a resistor connected across the terminals of the coil 24. One terminal of the resistor is connected through a grid-biasing device 60 to the common conductor for the filaments of the tubes. The adjustable contactor of the potentiometer 57 is connected to the grid of the tube 26.

The tube 26 is resistance coupled to the input of the transformer 56, this coupling comprising the resistor 61 and the condenser 62. The coupling is completed by the connection 63 between the link circuit and the common conductor for the filaments.

The output circuit from the tube 53, at the exit of the amplifier 20, is connected to the magnet 22 through a phase-control device. As illustrated, the phase-control device is a high-pass filter including condensers 65 and 66 in series, with an inductor 67 in shunt. The filter is so designed that its cut-off frequency is close to the natural frequency of the fork 23, consequently, small changes in the value of the inductance in the filter will

cause relatively large changes in the phase of the current in the magnet 22.

A portion of the inductor 67 is shunted by the plate-filament space of the tube 68. The conductivity of this space is controlled by the grid, which is connected through the grid-biasing device 60 to the common conductor for the filaments. The device 60 affords an adjustable potential and the shunting effect of the tube 68 upon the inductor 67 is controlled by adjustment of said potential.

The frequency multipliers indicated at 10 and 30 in Fig. 1 may be of any desired type, but the type illustrated in Fig. 3 is preferred. The conductors 71 extend from the coil 24 in Fig. 2 to the input of the first tube 72 of the frequency multiplier. The tube 72 acts as an amplifier and is connected in cascade with the tube 73.

The output circuit of the tube 73 contains a condenser 75 shunted by an inductor 76. This condenser and inductor are of such magnitude that together they form a parallel-resonant circuit for the frequency delivered to the coil 24 by the fork 23. That the resonance frequency is low is indicated on the drawing by showing a heavy iron core for the inductor 76. The other parallel-resonant circuit in the plate circuit of the tube 73 includes a condenser 77 and an inductor 78, which together form a parallel-resonant circuit for the frequency of a harmonic of the input to the tube 73. The grid of the tube 79 is connected to the point 80 between the two parallel-resonant circuits in the plate circuit of the tube 73.

The circuit 75-76 offers a very large impedance to the fundamental frequency, and only a small impedance to the harmonic frequency, while the circuit 77-78 offers a very large impedance to the harmonic frequency and but little impedance to the fundamental frequency. Consequently, the voltage impressed upon the grid of the tube 79 is almost entirely of the harmonic frequency.

In an embodiment of this invention which has been placed in practical operation, the parallel-resonant circuit 77-78 has a natural frequency three times that of the parallel-resonant circuit 75-76.

The tubes 82 and 84 are connected in cascade relation with the tube 79 to form an amplifier. The transformers in this amplifier are designed to carry the harmonic frequency to which the circuit 77-78 is tuned. They, consequently, contain less iron in their cores than the transformer in the amplifier including tubes 72 and 73.

Similarly the output circuit of the tube 84 contains two parallel-resonant circuits, one 85 being resonant to the fundamental frequency of the input of the tube 84 and the other 86 being tuned to a harmonic thereof. In the practical embodiment mentioned

above, the natural period of the circuit 86 is seven times that of the circuit 85. The tube 89 is related to the tube 84 in a way analogous to the relation of the tube 79 to the tube 73 and the tube 89 is the first of a pair of tubes 89 and 90 forming an amplifier which is adapted to transmit the frequency of the circuit 86. The transformer in this amplifier is, therefore, designed for even a higher frequency and its core should have little or no iron.

The output of the circuit 90 includes a parallel-resonant circuit 92 tuned to the same frequency as the circuit 86 and a parallel-resonant circuit 93 tuned to a harmonic thereof. In the embodiment mentioned above, the natural period of the circuit 93 is seven times that of the circuit 92. The tube 95 is related to tube 90 in a manner similar to that in which tube 79 is related to the tube 73. The tube 95 therefore, amplifies a frequency higher than any of the preceding tubes. It is connected to the next tube by a radio-frequency choke coil 96 and a condenser 97.

The tube to which the condenser 97 is connected is the power tube of the oscillator 31, Fig. 1. It may be a single power tube or a battery of power tubes arranged in parallel as desired.

The natural frequency of the fork 23 is maintained as nearly constant as possible. In order to accomplish this the fork is encased in a housing 100 of heat-insulating material, for example a wooden box. Within the housing a lamp 101 is provided to maintain the box at a higher temperature than its surroundings.

A second lamp 102 preferably smaller than the lamp 101 is located outside the casing at any point convenient for observation. For example, it may be mounted upon the top of a box. The circuit for the lamps is connected to any suitable constant source of power. A thermostatic circuit controller 103 situated within the box 100 establishes a shunt about the lamp 102 whenever the box is cool and opens said shunt upon sufficient rise of temperature within the box. When the shunt is established a larger current flows through the lamp 101 and consequently the box is heated more. The lamp 102 then is dark. When the shunt is open the lamp 101 receives less current and the lamp 102 glows brightly indicating that the box is cooling. The fork 1, at the station exercising the control, is preferably equipped with similar provisions for maintaining a constant frequency.

In the operation of the device, supplying energy to the amplifier 3 in Fig. 1 sets the fork 1 into vibration. The movement of the tines toward each other causes an increase in the flux through the coil 2 and the movement of them away from each other causes a diminution of the flux in the coil 2. The changes in flux produce changes in the electromotive

force delivered by the coil 2 to the amplifier 3. The action of this amplifier impresses upon the magnet 4 current which is at the same frequency as the output from the coil 2. The fork is thus maintained in oscillation.

The body 5 of magnetic material between the tines prevents the fork from vibrating like a pendulum about its standard. Such movement would cause the right hand tine to approach the body 5 while the left hand tine recedes from it. One air gap is, therefore, decreasing at the time, the other air gap is increasing. The resultant change in flux, is, therefore, either zero or very small. On the other hand, where the tines approach each other both air gaps become short and when the tines recede from each other both air gaps become long. Marked changes in flux are thus caused. The regenerative connection through the amplifier 3 is thus effective for the usual motion of the fork and ineffective for the pendulum-like motion.

The frequency generated by the fork is impressed upon the frequency multiplier 10 and multiplied by it. The resultant high frequency is further amplified by the oscillator 11 and impressed upon the antenna 12. In the embodiment of the system referred to above, the natural frequency of the fork 1 is only slightly less than 4000 cycles per second. The multiplying action of the frequency multiplier 10 in said embodiment is of the magnitude stated in connection with Fig. 3 and consequently produces a total multiplication by 147, giving for the frequency in the antenna 12 some 570 kilocycles.

The oscillation generator 7 may be controlled in frequency by a similar frequency multiplier governed by the same fork 1, but this is not necessary. Any source of high frequency oscillations will serve for this oscillator. The frequency chosen in the embodiment mentioned above corresponds to a wave length of some 65 meters. The 65-meter radiation is modulated at the frequency of the fork, somewhat less than 4000 cycles. This modulated 65-meter radiation is received upon the antenna 15 which in the above mentioned embodiment is some thousand miles from the antenna 8 and about one mile from the antenna 32.

The receiving set 16 produces from the energy received upon the antenna 15 an output current of about 4000 cycles, that is, of a frequency corresponding exactly to the frequency of the fork 1.

The receiving set may be adjusted by an attendant stationed near the antenna 15, but this is not always necessary. The receiving set may be controlled from the station at the antenna 32 by manipulating the key 48. Any suitable switching or remote-control device may be associated with the receiving set 16 to enable the operator at the broadcasting sta-

tion at the antenna 32 to control the adjustment of the receiving set 16, at the antenna 15. The amplifier 17 at the receiving station increases the fork-frequency current to a 5 value transmitted readily over the line 18 which is long enough to permit the antenna 15 to be well separated from the antenna 32 but not long enough to cause serious difficulty in transmitting current of this frequency. 10 In the above embodiment, it is about a mile long. The filter 19 is a high-pass filter. It is designed not only to compensate for the attenuation in the line 18 but to prevent extraneous frequencies which may have entered 15 the line 18 from being impressed on the amplifier 20. The frequency delivered by the filter 19 is the frequency of the fork 1. The transformer 45 and the output transformer of the filter permit the impedance of the line 18 20 to be balanced with the impedance of the input circuit of the tube 50.

The current of fork frequency received from the filter 19 is amplified by both portions of the amplifier 20 and then impressed 25 upon the driving magnet 22. In the construction illustrated in Fig. 2, the second part of the amplifier 20 acts as the regenerating amplifier for the fork 23. It is not, however, necessary that the amplifier for 30 regenerating the fork 23 shall be a portion of the amplifier which increases the current delivered from the filter 19. If these two amplifiers are separate it is possible to adjust one without disturbing the adjustment 35 of the other which has advantages in some circumstances.

When the amplifier, which forms a portion of this regenerative connection, is separated from the amplifier which cooperates 40 with the filter 19, the degree of regeneration may be adjusted without altering the degree of amplification applied to the impulses received from the receiving set 16. In this way, it is possible to vary the ratio between 45 the two sources of energy acting upon the fork. It is desirable that the impulses received from the receiving set shall have a control greatly exceeding the regenerative control.

50 The magnet 22, because the current which it receives is of the frequency determined by the fork 1, impresses upon the fork 23 impulses which correspond nearly to the natural frequency of this fork.

55 The fork 23 is thus set into vibration. The interaction of the tines and the magnetic member 25 induces in the coil 24, as explained in connection with the fork 1, an electromotive force of the same frequency.

60 The electromotive force from the coil 24 is impressed across the grid and filament of the tube 26. Adjustment of the potentiometer 57 will serve to regulate the magnitude of the electromotive force delivered to the grid of the tube 26. The output of the tube

62 is impressed through the condenser 62 and the transformer 56 upon the input of the tube 52. It is then amplified by the right-hand portion of the amplifier 20 and so impresses upon the magnet 22 a current which 70 serves to assist in keeping the fork 23 in oscillation.

The adjustment of the potentiometer 57 and the design of the amplifier are so chosen that the regeneration in the system, comprising fork 23, coil 24, amplifying system and magnet 22, is between the degree which will prevent rapid damping and the degree stated hereinafter. Moreover, the natural frequency of the fork 23 differs but slightly 75 from the frequency delivered by the transformer 55 to the system. As explained below, the system includes means whereby the natural period of the system can be adjusted and so made even closer to the period of the 80 current from the line 18.

The forks 1 and 23 are so constructed as to have as nearly as possible the same natural period. In addition to this, the forks are maintained at very nearly the same temperature. The small difference in frequency, which remains after these precautions are all taken, is removed almost completely by an adjustment of the phase relation between the output of the amplifier 20 and the current in the magnet 22. I have found it possible by the adjustment of this phase to change the period of oscillation of the system including the fork 23, the regenerating tube 26, the amplifier tubes 52 and 53 and the magnet 22 by as much as five cycles where the natural period of the fork 23 is in the neighborhood of 4000 cycles. If desired a similar provision for adjusting the fork frequency may be provided at the fork 1.

The adjustment of the phase relation is accomplished by adjusting the biasing potential upon the grid of the tube 68. This changes the internal impedance of the tube 68 and thereby alters the effectiveness with 105 which it shunts a portion of the inductor 67. The inductance of the combination of inductor and tube in parallel is thereby altered and thus results in a slight alteration of the cut-off frequency of the filter comprising 110 condensers 65 and 66 and inductor 67. This filter is so designed that its cut-off frequency is very nearly equal to the natural frequency of the fork 23. Consequently, a very small change in the inductance will result in a 115 very considerable change in the phase relation between the electromotive force delivered by the amplifier 20 and the current in the magnet 22.

120 Any phase-changing device may be used instead of the filter just described, although I have found such a filter preferable. Also the phase-changing device may be located at any point in the regenerative system from the coil 24 to the magnet 22. For example, it 125

may be inserted between the coil 24 and the input to the tube 26 or between the output of the tube 26 and the input to the tube 52.

- The impulses received from the receiving set 16 change their intensity with changes in atmospheric conditions between the antenna 8 and the antenna 15. Fading may cause these impulses to become so small that they can no longer produce perceptible effect.
- 10 When this occurs, the fork 23 will continue to oscillate because of the regenerative connection through the tube 26 to the magnet 22. If the degree of regeneration is only very slightly less than the damping, the fork will slowly diminish its amplitude and may finally come to rest, but it is quite possible to so adjust the regeneration that the period required for the fork to come to rest is longer than the time during which any ordinary fading will cause the impulses from the receiving set to be ineffective. This tendency of the fork to persist in vibration, thus is a means for keeping the broadcasting station at the proper frequency during the time that the fading persists.

With a properly chosen degree of regeneration, it is possible to control the frequency of the fork 23 by the frequency of the impulses from the filter 19. For this purpose there must be sufficient regeneration to ensure that upon cessation of impulses from the filter 19 the motion of the fork will die out only very slowly, if at all.

If the regeneration be too great, for example if it cause a voltage at the magnet 22 greater than the voltage caused there by the impulses from the receiving set 16, such control is not possible.

The control can be obtained with any degree of regeneration between these limits if the frequency of the impulses from the filter 19 is sufficiently close to the frequency of the regenerative system. When these frequencies are very nearly equal, the control of the frequency of the fork by the frequency of the impulses from the filter will continue to be effective as the impulses become smaller until they become much smaller than would be required to reestablish such control, once the fork has reverted to the natural frequency of the regenerative system.

When the impulses from the filter become too feeble to control the fork, the latter changes to the frequency of the regenerative system and when the impulses from the filter again become of sufficient strength to establish control, the fork frequency changes to that of the impulses.

The system therefore affords a means for maintaining the frequency at the antenna 32 equal to the frequency at the antenna 12 even when large fading effects occur between antennæ 8 and 15 and even when the fading prevents all communication between these antennæ for several seconds at a time.

Static effects as well as fading effects cause changes in the output from the receiving set 16. These static effects are very largely eliminated by the filter 19. The filter therefore serves the double purpose of correcting the selective attenuation of the line 18 and eliminating to a large extent the static impulses.

The static impulses which are not eliminated by the filter are somewhat amplified by the amplifier 20 and produce an effect in the magnet 22, but this effect is wholly irregular and completely unrelated to the frequency of the controlling impulses originating in the fork 1. Consequently, these static impulses are without perceptible effect upon the movement of the fork 23 and without any effect upon the frequency of said movement.

Moreover, if it should happen that a succession of static impulses, resembling closely enough the regular impulses from the fork 1, should arrive at the amplifier 20, their effect upon the movement of the fork 23 would be only temporary. As soon as the static impulses are over or cease to simulate the controlling impulses, the controlling impulses would bring the regenerative system including the fork 23 back to the frequency of the fork 1.

The impulses received from the fork 1 through the coil 2 and the impulses received over the line 71 from the coil 24, energized by the fork 23, are multiplied in frequency and impressed upon the respective antennæ by the transmitter sets 11 and 31.

The multiplying device is illustrated in Fig. 3. The low frequency currents received from the fork are amplified to such extent that the output of the last amplifier, the tube 73 as illustrated, is highly distorted. This distortion will be the cause of numerous harmonics. Because the tuned circuit 75-76 is parallel-resonant to the fundamental, the potential of fundamental frequency will be largely absorbed in this circuit. The point 80, therefore, will receive only very small potential changes of this frequency. Because the parallel-resonant circuit 77-78 is tuned to the frequency of the selected harmonic, the potential of the frequency changes between the point 80 and the filaments will be large, but potential changes of other frequencies will be small.

Consequently, the potential imposed upon the grid of tube 79 will be almost entirely of the frequency of the selected harmonic. This frequency in its turn is amplified and a similar action by the circuits 85 and 86 will impress a higher harmonic upon the grid of the tube 89. This in its turn will be multiplied by the parallel-resonant circuits 92 and 93, producing upon the grid of the tube 95 potential-changes of a frequency sufficiently high to serve for the transmitting action of the antenna. This frequency is delivered,

over the condenser 97, to the oscillator 31 and, in the case of the multiplier 10 over a similar condenser, to the oscillator 11. In this way, radio-frequency oscillations of the same frequency are produced in the two antennæ.

The signals from the microphone 35 are transmitted over the line 37 to both broadcasting stations. The filters 41 and 38 are designed to correct the selective attenuating action of the lines. The energy impressed upon the modulators 39 and 42, therefore, is of a quality nearly unaffected by the line transmission. These modulators cause similar and simultaneous variations in intensity at the two broadcasting stations.

Consequently, any receiving set located within the reach of both stations will receive the same signal upon the same wave length modulated in the same way from either station or from both stations simultaneously. If fading causes the signal from one broadcasting station to disappear altogether, the signal from the other broadcasting station will continue to operate the receiving set, the listener will be unaware of any effect due to the fading.

The regenerative constant-frequency generator disclosed in this application is described and claimed in my copending application Serial No. 238,824, filed December 9, 1927, and assigned to the Westinghouse Electric & Manufacturing Company.

Although I have described in detail but a single embodiment of my invention and have mentioned only a few modifications thereof, it will be evident to those skilled in the art that many other modifications are possible and I, therefore, do not intend any limitation, except such as is required by the prior art or stated in the claims.

I claim as my invention:

1. In a radio system, a broadcasting station, a second broadcasting station remote therefrom, means for maintaining said stations at the same carrier frequency comprising an oscillating system at one station and a regenerative oscillatory system stimulated thereby at the other station.

2. In a radio system, a broadcasting station, a second broadcasting station remote therefrom, means for maintaining said stations at the same carrier frequency comprising an oscillating system at one station and a regenerative oscillatory system stimulated thereby at the other station, the degree of regeneration being sufficient to cause the regenerative system to continue in oscillation after stimulation thereof has become ineffective for at least as long a time as fading can ordinarily render said stimulation ineffective.

3. In a radio system, a broadcasting station, a second broadcasting station remote therefrom, means for maintaining said stations at the same carrier frequency comprising an oscillating system at one station and

a regenerative oscillatory system stimulated thereby at the other station, the degree of regeneration being sufficient to cause the regenerative system to continue in oscillation after stimulation thereof has become ineffective for at least as long a time as fading can ordinarily render said stimulation ineffective, and insufficient to cause said regenerative system to build up oscillations large compared with said stimulation.

4. In a radio system, a broadcasting station, a second broadcasting station remote therefrom, means for maintaining said stations at the same carrier frequency comprising an oscillating system at one station and a regenerative oscillatory system stimulated thereby at the other station and high frequency oscillations one at each station each controlled by the said oscillating system at its station.

5. In a radio system, a broadcasting station, a second broadcasting station remote therefrom, means for maintaining said stations at the same carrier frequency comprising an oscillating system at one station and a regenerative oscillatory system stimulated thereby at the other station, frequency multipliers of like multiplying power associated respectively with said oscillating systems, and high-frequency oscillators governed by said frequency multipliers, whereby the high frequency at each station is the same multiple of the frequency of the said oscillating system at one station.

6. In a radio system, a broadcasting station, a second broadcasting station remote therefrom, means for maintaining said stations at the same carrier frequency comprising an oscillating system at one station and a regenerative oscillatory system stimulated thereby at the other station, frequency multipliers of like multiplying power associated respectively with said oscillating systems and high-frequency oscillators governed by said frequency multipliers, whereby the high frequency at each station is the same multiple of the frequency of the said oscillating system at one station, a source of signals, modulators, one at each station, for the respective high-frequency oscillators there and a communication channel connecting said source of signals to each modulator, whereby the broadcasting from each station is on the same carrier wave length modulated in the same way.

7. In a frequency control system a frequency-determining device including a member having a characteristic period of mechanical oscillation, a second frequency-determining device including a member having a characteristic period of mechanical oscillation of approximately the same magnitude as the first-mentioned member, means including a thermionic tube for adjusting the frequency determined by the first-mentioned

frequency-determining device to bring it to as nearly as possible the frequency of the second-mentioned frequency-determining device and means controlled by the second-mentioned frequency-determining device for maintaining the first-mentioned frequency-determining device at the frequency determined by the second-mentioned frequency-determining device.

10 In testimony whereof, I have hereunto subscribed my name this 21st day of November, 1927.

LESTER J. WOLF.
